[57] CLAIM

The ornamental design for a stand for a mixer, as shown and described.

DESCRIPTION

FIG. 1 is a perspective view of a stand for a mixer showing our new design, the broken line showing of the mixer being for illustrative purposes only;
FIG. 2 is a front elevational view thereof;
FIG. 3 is a left side elevational view thereof;
FIG. 4 is a top plan view thereof;
FIG. 5 is a rear elevational view thereof; and
FIG. 6 is a fragmentary sectional view thereof taken on line 6—6 of FIG. 4.
